UNITED STATES PATENT OFFICE

2,293,105

POWER TAKE-OFF FOR AIR CIRCULATING MEANS

Charles D. Bonsall, Chicago, Ill., assignor to Standard Railway Equipment Manufacturing Company, Chicago, Ill., a corporation of Delaware

Application February 15, 1941, Serial No. 379,004

2 Claims. (Cl. 74—13)

The invention relates to railway refrigerator cars and more particularly to such cars having fans in the lading or refrigerant compartment thereof for causing a circulation of air within the car for refrigerating, heating or ventilating the lading in the car wherein a pulley engages a wheel or axle of the truck of the car so as to be revolved thereby. Means are provided between the pulley and fan whereby revolution of the pulley revolves the fan.

A typical example of such a fan equipped refrigerator car is shown in Schwebs No. 2,136,894 of November 15, 1938.

A conventional refrigerator car is swivelly supported by trucks adjacent the opposite ends of the car so that the trucks may swing in a horizontal plane when the car rounds a curve in the track. One of the objects of the invention is to provide means to retain the above mentioned pulley in engagement with the wheel or axle of the truck when the car goes around a curve. A further object is to provide means attached to the car body and associated with the truck so as to move therewith and maintain the pulley in operative relation with the wheel or axle of the truck.

Vertically acting springs are associated with the truck to absorb the shocks of a moving car over a rough and uneven track and to yieldingly resist the tendency of the car to sway in service. Therefore, a further object is to provide means for the truck to move vertically relative to the car body without disengaging said pulley from said wheel or axle.

A further object is to provide means to temporarily disengage said pulley from said wheel or axle so that, if desired, the car may be moved along the track without actuating the means which operates the fan. This is also desirable so that the fan operating means may be actuated when the car is standing still by driving the pulley with an electric motor while precooling the lading. The lading is precooled, as it is called by the trade, by icing the bunkers and circulating air by means of a fan between the ice compartment and the lading compartment. This is done while the car is standing still; that is, before it starts moving to its destination.

Another object is to provide means to support such a pulley from the car body independently of the car truck so that a truck may be removed and replaced without disturbing the pulley or its associated elements.

A further object is to provide means in such a railway refrigerator car to attach the pulley to

the body of the car so as to provide universal movement between the pulley and the car body so that the pulley will remain in engagement with the wheel of the truck during the numerous and various relative movements between the car body and the truck.

Other objects and advantages of my invention will be apparent from the following detailed description by referring to the accompanying drawings.

In the drawings:

Fig. 1 is a longitudinal section through a part of the body of a refrigerator car showing the truck in an elevational view and showing my invention applied to the car.

Fig. 2 is a portion of Fig. 1 drawn to an enlarged scale.

Fig. 3 is a section on line 3—3 of Fig. 2.

Fig. 4 is a view similar to Fig. 2 showing a modified construction.

The general parts of the refrigerator car shown include roof 2, floor 3, end wall 5 and bulkhead 6 spaced from the end wall 5 to divide the interior of the car into a refrigerant bunker 8 and a lading compartment 9. A similar bunker is preferably provided at the opposite end of the car. The bulkhead 6 is spaced from the roof 2 and floor 3 to provide openings 11, 12 for air circulation between the bunker 8 and lading compartment 9. A fan 14 is provided, preferably in the upper opening 11, to induce or accelerate such circulation of air and means are provided for driving the fan. Such means, in the preferred form shown, comprises a hydraulic turbine 15 operatively connected to the fan 14 and driven by a fluid pumped under pressure to the turbine from a pump 17 driven by means hereinafter described. The pressure line from pump to turbine is indicated by (18) and the return line by (20), a reservoir 21 preferably being provided in the return line 20. The fan 14 may be driven by other means, such as a flexible shaft, if desired.

The underframe of the car includes the center sill 25 and body bolster 26 and the floor stringers 28 are supported in part by the bolster 26. The body bolster 26 is swivelly supported upon the truck bolster 29 which in turn is yieldingly supported on the truck side frames 31 by the helical springs 32 interposed therebetween. The side frames 31 are provided with bearings 34 on their opposite ends in which are journaled axles having the wheels 35 mounted thereon. A similar truck is provided at the opposite end of the car.

In the form of my invention disclosed herein, the pulley 40 is pivotally mounted upon one

end 41 of a link 43 and operatively connected to the pump 17. The other end of the link 43 is pivotally mounted (44) upon a swivel member 46 having an upper horizontal surface 47, which loosely and slidably engages a horizontal surface 49 of a base member 50 which is secured to some part of the car body, such as the stringer 28. The members 46, 53 are held together by bolts 52 which pass through round holes 53 in one of said members 50 and slotted holes 54 in the other of said members 46. A ball 55 engaging races in each of said members 46, 50 may be provided to reduce friction.

When the wheel 35 moves vertically in relation to the car body due to the deflection of the helical springs 32, the pulley 40 and link 43 swing around the pivot 44. When the truck moves laterally of the car body (when the car rounds a curve) the swivel member 46 pivots around the center of the base member 50, or the ball 55 if one is used. By this construction, a universal movement is provided between the pulley 40 and the car body, thus keeping the pulley 40 in operative engagement with the car wheel 35 in any service position of the car body relative to the car truck.

In order to maintain a uniform pressure between the pulley 40 and the car wheel 35, a helical spring 60 is interposed between the link 43 and a ledge 61 extending outwardly from the swivel member 46.

When it is desired to move the car without operation of the fan 14, or when it is desired to drive the pump 17 and fan 14 with an extraneous motor during periods when the car is not moving, the pulley 40 is disengaged from the wheel 35 by lifting the link 43. The link 43 is provided with a hook 65 which may be attached to the hook 66 depending from the car body to maintain the pulley 40 out of engagement with the car wheel 35. Means are preferably provided for the attachment of an extraneous motor 68 arranged to drive the pump 17 when the car is not moving and the friction wheel 40 and car wheel 35 are disengaged.

In the modification shown in Fig. 4, the link is in the form of a U-shape member 70 having the

5 pulley 40 mounted between the open ends 71 of the member 70. A member 73 having an eye 74 is secured to the stringer 28 and the closed end 76 of the U-shape member 70 is pivotally engaged through the eye 74 of the member 73, thereby permitting the member 70 to swing in any direction. A tie 77 is preferably provided to maintain the members 70, 73 in engagement.

10 The accompanying drawings illustrate the preferred form of the invention, though it is to be understood that the invention is not limited to the exact details of construction shown and described, as it is obvious that various modifications thereof, within the scope of the claims, will occur to persons skilled in the art.

15 I claim:

1. A power take-off device for transmitting power from the wheel of a railway car truck to a mechanism for operating an air circulating fan in the car, said device comprising a pulley 20 engaging a wheel of the car truck, means to attach said pulley to the body of the car, said means providing universal movement between the pulley and the car body so that said pulley will remain 25 engaged with said wheel during the various relative movements between the car body and the car truck, said pulley adapted to be operatively associated with mechanism for operating an air circulating fan in the car, said means comprising a base member secured to the car body and provided with a lower horizontal surface, a swivel member having an upper horizontal surface loosely engaging said lower surface of the base member, said members being attached together 30 for relative movement about a vertical axis, and a link having one end thereof pivotally connected to said lower member and the other end thereof pivotally connected to said pulley.

35 2. A structure as defined in claim 1 including a spring interposed between said swivel member and said link to yieldingly maintain said pulley in engagement with said wheel during said universal movement.

CHARLES D. BONSALL.
